UNITED STATES PATENT OFFICE.

THOMAS O. RAWLINGS, OF KANSAS CITY, MISSOURI.

DESIGN FOR A COMBINATION-TOOL.

SPECIFICATION forming part of Design No. 30,892, dated May 30, 1899.

Application filed April 29, 1899. Serial No. 715,060. Term of patent 14 years.

To all whom it may concern:

Be it known that I, THOMAS O. RAWLINGS, a citizen of the United States, residing at Kansas City, in the county of Jackson and State of Missouri, have invented a new and useful Design for Combination-Tools, of which the following is a specification.

My invention relates to a new and useful design for combination-tools.

10 In the accompanying drawing, which illustrates in perspective a combination-tool showing my new design, the leading or material feature resides in a substantially T-shaped figure with one branch or arm of the head portion tapering to a point and the other substantially of flaring or bell-shaped formation, the foot end of the stem of said T-shaped figure curving downward and terminating in a web-foot-shaped figure, said figure extending substantially parallel with the stem of the T-shaped figure.

15 Minor features of my design are comprised in a curved neck portion uniting the stem and head portion of the T-shaped figure and an

arm depending from the stem of said T-shaped figure.

20 Referring to the drawing in detail, 1 designates the stem, and 2 the neck, of the T-shaped figure.

3 designates the tapering or pointed arm, 30 and 4 the flaring or bell-shaped arm, forming the head of the T-shaped figure.

5 designates the web-foot-shaped portion of the tool, and 6 the curved or bent portion uniting said web-foot portion to the foot of 35 the stem 1.

7 designates the arm depending from the stem of the T-shaped figure.

What I claim is—

25 The design for a combination-tool, as herein shown and described.

30 In testimony whereof I affix my signature in the presence of two witnesses.

THOMAS O. RAWLINGS.

Witnesses:

M. R. REMLEY,
H. C. RODGERS.
